UNITED STATES PATENT OFFICE.

HENRY PERVILHAC, OF VILLEURBANNE, FRANCE.

COLOR-PRINTING MACHINE.

1,134,697.

Specification of Letters Patent. Patented Apr. 6, 1915.

Application filed July 18, 1914. Serial No. 851,737.

To all whom it may concern:

Be it known that I, HENRY PERVILHAC, a citizen of the French Republic, residing at Villeurbanne, Rhône, in France, have invented certain new and useful Improvements in Color-Printing Machines, of which the following is a specification.

This invention relates to improvements in color printing machines.

10 In the known machines for printing fabrics in several colors, the engraved or color printing cylinders are pressed against the periphery of a single cylinder, each of said engraved cylinders is provided with its pressure and inking mechanism and as they are situated at different heights the arrangement of such mechanisms differs for each cylinder which complicates the construction and the operation. Further, supervision is 15 rendered difficult by the height and the complicated nature of the machine frame.

In the present machine all the engraved or pressure cylinders are arranged on the same horizontal plane and can be simultaneously pressed by a single movement, also supervision of the inking of each engraved cylinder as well as of the result on the fabric after each impression can be easily effected.

20 In the old machines, the engraved rollers are liable to bend owing to the great pressure thereon to make the color penetrate into the fabric. In the present invention this fault is obviated by the fact that each of the 25 rollers is pressed equally along all its length while it is pressed between two other rollers. This arrangement allows the suppression of the roller known as the water roller which is made use of in certain cases to cause the 30 color to penetrate into the fabric. The construction naturally obliges the color to be compressed after having been printed, and it also allows a very rapid unmounting and changing of the rollers and repairs to be 35 easily effected.

The annexed drawing illustrates the arrangement of a four color machine.

Figure 1 is a side elevation of the machine. Fig. 2 is a plan view. Fig. 3 is a transverse 50 section.

Between two parallel frames 1, 1 the shafts 2, 2 are mounted in a horizontal plane and carry on oscillatory standards 3, the engraved cylinders 4, the axles 7 of which 55 rotate in bearings 7^a secured by the caps 5.

The standards 3 are provided with lateral

projections 3^a which carry the pressing cylinders 6; the bearings 6^a of which can slide freely in horizontal slides 6^b of said lateral projections. At each end of the frame 1 a pressing roller 8 is mounted of which the bearings 9 can slide horizontally in slides 10, and are operated by screws 11. These screws are coupled by suitable means not illustrated, so as to be operated simultaneously. The standards 3 also carry supports 12 intended to receive plates or scrapers 13 which bear on the engraved cylinders; it is in the angle formed by the scraper and the surface of the cylinder that the different colors are arranged in a suitable plastic state for filling the hollows of the engraving, the action of the scrapers is facilitated by reciprocating movement imparted to them by cams 14 keyed on the ends of the axles of the pressure rollers 6. By actuating the screws 11 the entire series of cylinders 8, 6, 4, will be pressed together. To render this pressure quite regular an elastic member or spring 11^a is arranged 75 between the respective screws 11 and the bearings 9.

A movement of rotation is given to the engraved cylinders by means of helicoidal wheels 15 mounted on the shaft 16 and 80 gearing with wheels 17 driving the cylinders. The fabric 18 to be printed is unwound from the roller 19 at a suitable tension, passes successively over the presser roller 6 and under the engraved cylinders 4 where it receives the successive impressions and is wound finished on the roller 20 driven by suitable gearing; it is accompanied during its movement by a blanket or duplicate 85 21 which is unwound from the roller 22 and is wound on to the roller 23. This blanket prevents the color from being deposited on the presser rollers; during its passage it passes over the rollers 24 rotating freely on the axles 2 of the standards 3.

90 It is understood that the impressions of the cylinders must register and to effect this, means are provided allowing adjustment of the cylinders in two directions. The transverse adjustment is obtained (Fig. 3) by 95 causing the shafts 2 which carry the standards 3 to slide axially. For this purpose these shafts have one of their ends screw threaded and engaged in a nut 25 boxed in the frame 1 and rotated by a hand wheel 26.

100 The longitudinal displacement is obtained by a rotary displacement of the cylinder

with regard to its driving wheel 17, Fig. 3. For this purpose the wheel 17 is fixed to the cylinder shaft by means of a helicoidal wheel 27 keyed on said shaft and a worm 28 rotatable in a cage fixed to the wheel 17. It can be understood that it is sufficient to turn the worm in one or other direction to adjust an engraved cylinder with respect to the preceding one. In order to allow transverse displacement of a cylinder, the shaft 7 can slide without turning in the sleeve of the wheel 27 which itself is maintained in place by a circular collar 28^a in the groove of which a fixed bar 29 engages.

15 The machine may be constructed for as many colors as required without complicating the construction nor hindering the supervision. The changing of the cylinders can be effected by removing the caps 5. The 20 lowness of the frame and its simple construction allows a simultaneous view of all the rollers and renders the regulation and supervision very easy. If desired liquid colors could be used by placing below each 25 engraved cylinder a suitable inking apparatus of known kind. The machine can be used for printing all kinds of fabrics, papers or other materials in sheet form.

What I claim as my invention and desire 30 to secure by Letters Patent of the United States is:—

1. In a machine for printing a plurality of colors, the combination of a frame, a plurality of printing rollers arranged in the 35 same horizontal plane and parallel to one another, pressing rollers disposed laterally of said printing rollers and lying in the same horizontal plane therewith, means for supporting said printing and pressing rollers, and means for simultaneously pressing 40 said printing and pressing rollers together.

2. In a machine for printing a plurality of colors, the combination of a frame, a plurality of printing rollers arranged in the 45 same horizontal plane and parallel to one another, pressing rollers disposed laterally of said printing rollers and lying in the same horizontal plane therewith, means for 50 supporting said printing and pressing rollers, means for simultaneously pressing

said printing and pressing rollers together, and means for axially and circumferentially adjusting said printing rollers for registering purposes.

3. In a machine for printing a plurality of colors, the combination of a frame, a plurality of shafts mounted in said frame in the same horizontal plane, guide rollers on said shafts, standards mounted on said shafts, a plurality of printing rollers arranged in the same horizontal plane and parallel to one another, removably mounted in said standards, pressing rollers slidably mounted in said standards on each side of said printing 65 rollers, and in the same plane therewith, means for simultaneously pressing said printing rollers and pressing rollers together, means for axially and circumferentially adjusting said printing rollers for registration purposes, and means for distributing coloring matter to said printing rollers.

4. In a machine for printing a plurality of colors, the combination of a frame, a plurality of shafts mounted in said frame in the 75 same horizontal plane, guide rollers on said shafts, standards mounted on said shafts, a plurality of printing rollers arranged in the same horizontal plane and parallel to one another removably mounted in said standards, pressing rollers slidably mounted in said standards on each side of said printing rollers, and in the same plane therewith, a guide disposed at each end of the series of printing and pressing rollers, horizontally 80 movable bearings mounted in said guides, rollers mounted on said bearings, screws mounted in said guides adapted to move said bearings to cause said last mentioned rollers to press said printing and pressing rollers together, means for axially and circumferentially adjusting said printing rollers for registration purposes, a scraper for each printing cylinder and means for imparting reciprocating movement to said scrapers.

In witness whereof I have signed this specification in the presence of two witnesses.

HENRY PERVILHAC.
